Attorney

UNITED STATES PATENT OFFICE

ALPHONSE J. NAVARRE DE REQUESENS, OF NEW YORK, N. Y.

HAIR STRAIGHTENING DEVICE

Application filed May 12, 1932. Serial No. 610,921.

This invention relates to means for straightening hair.

One of the features of the invention resides in a means whereby natural curly or kinky hair may be straightened to enable dressing of the same in modern styles and is especially adapted for use in straightening the hair of the feminine sex.

It is well known that when straight hair is wound upon a hair winding stick and subjected to heat while in such wound condition will cause the same to become curly and which system is common in the art of permanent waving. It is my purpose to utilize this system to straighten curly hair by tightly winding the curly hair lengthwise of a stick to secure the same in straight lengths and then subjecting the hair so held to the action of heat.

Another feature is the provision of a hair winding stick having sets of hooks on opposite sides thereof, the set on one side being staggered with respect to the set on the opposite side to enable the compact looping of a hank of curly hair thereon.

A further object of the invention is the provision of a hair straightening device which is simple of construction, inexpensive of manufacture, and which may be used in association with the conventional forms of permanent hair waving machines.

Other objects of the invention will appear as the following specification is read in conjunction with the accompanying drawing, in which:

Figure 1 is a perspective view showing my invention in use.

Figure 2 is a side elevational view of my improved hair straightening stick with a hank of hair shown wound thereon.

Figure 3 is an edge elevational view of the same.

Figure 4 is a perspective view of the hair straightening device per se.

Figure 5 is an enlarged horizontal sectional view on the line 5—5 of Figure 2.

Referring to the drawing by reference characters, the numeral 10 designates my hair straightening device in its entirety which includes a flat elongated body 11 of aluminum

or other light metal and which is formed with a finger grip portion or handle 12 at one end, the said end being rounded. The opposite end of the body terminates in a small head 13 having a bifurcation or slot 14 formed therein, while inwardly of the slot is a groove 15.

The opposite sides of the flat body 11 are formed with sets of spaced hooks or notches 16, the hooks of one set being staggered with respect to the hooks of the other set. All of the hooks extend outwardly toward the ends of the body adjacent thereto.

In practice, assume that it is desired to straighten or remove the kink from a head of human hair.

The hair is arranged in hanks, and each hank is wound upon one of the straightening members 10. The head end 13 of the member is positioned approximately one inch from the scalp and the hank of hair A is secured thereto by a tie string 17, the winding of the string being seated in the groove 15. If desired the ends of the tie string may be slipped into the bifurcations or slot 14 to avoid tying of knots. With the member 10 attached to the hank of hair the said hank is wound lengthwise of the body 11 over and around the hooks 16 as best seen in Figure 2 of the drawing. When fully wound, the end of the hank may be secured by inserting the same under one of the lengths as shown, or a string (not shown) may be tied about the wound hair centrally of the body 11. During the arranging of the hair in this manner, the operator grasps the straightening member 10 by the handle 12. All parts are rounded to prevent injury to the head of the person being treated and to protect the operator during the arrangement of the hair thereon.

After the hank of hair A has been thus arranged, the member 10 with the hair thereon is placed in the heating element B of a permanent hair waving machine. These heating elements are heated either by steam or electricity, the purpose being to subject the straightened hair held on the member 10 to such heat as to cause the same to remain straight when unwound from the member. Heat is now employed to place a wave or

curl in naturally straight hair when curled upon a stick and it is my idea to remove a curl or kink from naturally curly or kinky hair by a similar process.

5 From the foregoing description it will be seen that I have provided a device by which curly hair may be held in straight lengths and subjected to the action of heat to render the said hair straight when removed from the device, and which is capable of use in connection with the present construction of permanent hair waving machines.

10 While I have shown and described what I deem to be the most desirable embodiment of my invention, I wish it to be understood that such changes as come within the scope of the appended claims may be resorted to if desired.

15 Having thus described the invention, what I claim as new and desire to secure by Letters Patent is:—

20 1. A hair straightening device comprising a flat elongated body, and sets of spaced notches formed in opposite sides of said body and the notches of each set facing opposite ends thereof.

25 2. A hair straightening device comprising a flat elongated body, sets of spaced hooks formed in opposite sides of said body, the sets of hooks on one side being staggered with respect to the hooks on the opposite side, the respective hooks of each set extending outwardly toward the adjacent end of said body.

30 3. A hair straightening device comprising a flat elongated body, sets of spaced hooks formed in opposite sides of said body, the set of hooks on one side being staggered with respect to the hooks on the opposite side, the respective hooks of each set extending outwardly toward the adjacent end of said body, and a handle extending from one end of said body.

35 4. A hair straightening device comprising a flat elongated body, sets of spaced hooks formed in opposite sides of said body, the set of hooks on one side being staggered with respect to the hooks on the opposite side, the respective hooks of each set extending outwardly toward the adjacent end of said body, and a handle extending from one end of said body, and means on the opposite end of said body by which the same may be attached to a hank of hair to be straightened.

40 In testimony whereof I affix my signature.

45 55 ALPHONSE J. NAVARRE de REQUESENS.
